UNITED STATES PATENT OFFICE.

PHILIPPE DE CLAMECY, OF BOSTON, MASSACHUSETTS, ASSIGNOR TO CORONA TYPE-WRITER COMPANY, INC., OF GROTON, NEW YORK, A CORPORATION OF NEW YORK.

TYPEWRITING-MACHINE.

1,355,820.

Specification of Letters Patent.

Patented Oct. 19, 1920.

Application filed January 26, 1918, Serial No. 214,618. Renewed October 21, 1919. Serial No. 332,253.

To all whom it may concern:

Be it known that I, PHILIPPE DE CLAMECY, a citizen of the United States, and a resident of Boston, county of Suffolk, and State of Massachusetts, have invented certain new and useful Improvements in Typewriting-Machines, of which the following is a specification.

This invention relates to improvements in typewriting machines, and more particularly to key actions for collapsible typewriting machines.

The invention has for one of its objects the provision of a collapsible type action in which the keys are adapted to actuate the type bars through collapsible key operated levers each having relatively foldable pivotally connected parts to permit the keys to be moved horizontally from their normal extended operative positions to more compact positions closer to the type bars without breaking the mechanical connection between the keys and type bars.

Another object of the invention is to provide a key action embodying key-operated levers having pivotally connected horizontally foldable sections to permit the keys to be shifted horizontally toward the rear of the machine.

Another object of the invention is to provide a key action embodying collapsible levers pivotally supported intermediate their ends and having constantly maintained mechanical connections with the keys and type bars.

A further object of the invention is to provide a key action embodying key-operated levers fulcrumed intermediate their ends on a horizontally shiftable support and operatively connected at their rear ends with the type carriers, said levers having collapsible sections both fore and aft of their fulcrums to permit the opposite ends of the levers and the support to be compacted into close relation with each other and with the type carriers.

Another important object of the invention is to provide a collapsible typewriting machine having a key action embodying a universal keyboard and collapsible key-operated levers operatively connected to actuate the type bars, and means whereby the banks of keys may be shifted relatively to each other to make the keyboard compact

and the compacted keyboard shifted bodily beneath the type bars.

Another important object of the invention is to provide a typewriting machine having a compactible key action and means whereby a uniform relative movement may be imparted to the parts of the key action when the key action is extended and compacted, and a further object is to provide a collapsible typewriting machine having a horizontally slid able keyboard frame part and lazy tongs mechanism operable by movement of the keyboard frame part into and out of the main frame for imparting a uniform relative movement between the several banks of keys of the keyboard.

In the drawings, Figure 1 is a fragmentary vertical sectional view of a typewriting machine provided with a key action embodying the invention;

Fig. 2 a fragmentary sectional plan view showing a portion of the key action in extended position;

Fig. 3 a view similar to Fig. 2, showing the parts in collapsed or compact position;

Fig. 4 a detail vertical transverse section showing a portion of the guiding and alining mechanism for the banks of keys;

Fig. 5 a view similar to Fig. 1, parts of the key action being omitted in order to show more clearly the guiding and alining mechanism for the banks of keys; and

Fig. 6 a view similar to Fig. 2, showing the key action in its collapsed or compact position.

The main frame part comprises a bottom plate 1 and side walls 2. Any desired form of type bar hanger may be provided, such as a curved rod 3 supported at its ends in the main frame part in any suitable manner. The type bars 4 are pivotally mounted at 95 their rear ends on the hanger 3, and the segmental basket of type bars may be normally supported in a horizontal position, to move upwardly and rearwardly to the printing point, in any suitable manner, as by a curved plate 5 supported in the main frame part and provided with a suitable cushion 6 for the heads of the type bars.

A keyboard support 7 is hinged to the bottom plate 1 of the main frame part at 105 8 to fold upwardly and rearwardly, said support being adapted to coöperate with the main frame part to inclose the key action

when the machine is collapsed. The keyboard is provided with three rows of keys 9, 10 and 11, supported in banks, and a space bar 12 supported in front of the banks of 5 keys, as is common in universal or standard keyboards. The space bar 12 is supported adjacent its ends on two vertically reciprocable stems or rods 13, preferably angular in cross section, and guided in angular 10 apertures in the front cross-bar 14 of a forwardly and rearwardly slidable substantially U-shaped keyboard frame, the side members 15 of which are slidably supported in guide-ways formed by inwardly projecting ribs or flanges 16 formed on the side walls 2 of the main frame. The space bar supporting rods or stems 13 are connected by horizontal pivot pins 17 with the front ends of two collapsible levers 18, pivotally 15 supported intermediate their ends on a pivot rod 19. The rod 19 extends transversely of the machine and is supported at its ends in standards 20 mounted on a slide 21 which is guided in ways 22 on the main frame. The 20 levers 18 are formed with laterally shiftable portions 18^a and 18^b forwardly of their pivotal points and with laterally shiftable sections 18^c and 18^d at the rear of their pivotal points. The several sections of the 25 levers 18 are pivotally connected together by vertical pivot pins 23, 24, 25, 26, 27 and 28, and said levers may be connected in any suitable manner to actuate a carriage escapement mechanism when the space bar 12 30 is depressed.

The front bank of keys 9 are mounted on angular vertically reciprocable key stems 29, guided in angular apertures in a transversely extending bar 30 slidably supported 35 at its ends in grooves or ways 31 formed in the inner faces of the side members 15 of the sliding U-shaped keyboard frame. The banks of keys 10 and 11 are mounted on angular key stems or rods 32 and 33, respectively, guided in angular apertures in transversely extending bars 34 and 35, slidably supported in ways or grooves 36 and 37, formed in the side members 15 of the keyboard frame above the 40 groove 31. Each key 9 is connected with its associated type bar 4 by a collapsible key lever 38, connected at its forward end with the key stem 29 by a horizontal pivot pin 39, and connected at its rear end by a horizontal pivot pin 40 with the lower end of a rigid link 41. Each link 41 is connected with its associated type bar 4 forward of the pivotal point of the type bar by a horizontal pivot pin 42. It will be understood 45 that the links 41 are bent or shaped in the usual manner to connect with the type bars supported on the curved rod or hanger 8. Each key lever 38 is pivotally supported intermediate its ends on a transversely extending rod 43 which is held at its ends in

the standards 20 carried by the slide 21. Each of the key levers 38 is formed with two laterally shiftable sections 38^a and 38^b in front of its pivotal point and with two laterally shiftable sections 38^c and 38^d at 70 the rear of its pivotal point, the several sections of each lever being connected by vertical pivot pins 44, 45, 46, 47, 48 and 49.

Each key 10 is connected with one of the 75 links 41 by a jointed and collapsible lever 50 of substantially the same construction as the levers 38, and each key lever 50 is pivotally supported intermediate its ends on a transversely extending rod 51 supported in the standards 20 above the pivot rod 43 of 80 keys 9. Each key 11 is connected with one of the links 41 by a jointed and collapsible lever 52 of substantially the same construction as the key levers 38 and 50, and each key lever 52 is pivotally supported intermediate its ends on a transversely extending rod 53 carried by the standards 20 on slide 21 directly above the pivot rods 19, 43 and 51.

The U-shaped keyboard frame is supported at its forward end on two posts 54, the upper ends of which are rigidly connected with the bar 14 adjacent its ends, and the lower ends of which are rigidly held to a slide 55. The sliding bar 30 is rigidly connected with a slide 56 by two posts 57, and the bars 34 and 35 are similarly connected with slides 58 and 59 by posts 60 and 61. The four pairs of posts 54, 57, 60 and 61 are connected at each side of the machine by a suitable lazy tongs mechanism comprising pairs of links 62 and 63 pivotally connected with each other at 64 and pivotally connected at their lower ends with the adjacent posts by pivot pins 65. The upper ends of the links 62 and 63 are pivotally held at 66 to sleeves 67 slidably held on the posts.

A slide 68 is mounted in the guideways 22 forwardly of the slide 21. The slide 21 is provided adjacent each end with a post 69 and a post 70 is mounted on slide 68 adjacent each end thereof. The posts 69 and 70 at each side of the machine are connected with each other and with the pair of posts 61 on slide 59 by a lazy tongs mechanism. This lazy tongs comprises pairs of links 71 and 72 pivotally connected at 73, and pivotally held to the posts at their lower ends. The links 71 and 72 are pivotally held at their upper ends to sleeves 74 slidably mounted on the posts 61, 69 and 70. When the key action is in its normal extended operative position the slides 21 and 68 are supported on the main frame part in the ways 22, and the slides 55, 56, 58 and 59 are supported in ways 75 formed on the hinged plate or support 7 and adapted to register with the ways 22 when said plate is in its unfolded position. The inner ends of the side members of the U-shaped keyboard frame are 130

- supported in the outer ends of the ways 16 when the key action is in its normal operative position. The slide 55 which supports the forward end of the keyboard frame is 5 preferably provided adjacent each end thereof with a suitable handle or finger piece 76.
- With the parts in their normal extended operative positions, as shown in Figs. 1, 2 10 and 5, when it is desired to collapse the key action and shift the keyboard to its compact inoperative position beneath the type bars, it is simply necessary to grasp the finger pieces 76 and push the slide 55 rearwardly along 15 the guideways 75 and 22 until the rear ends of the side members 15 of the keyboard frame abut against stops 77 formed at the rear ends of the guideways 16. As the keyboard frame and slide 55 move rearwardly 20 the lazy tongs connecting the posts 54, 57, 60 and 61 and the lazy tongs connecting the posts 61, 70 and 69 are collapsed, causing the plates or bars 30, 34 and 35 to move relatively to each other and to the bar 14 25 of the keyboard frame until said bars 30, 34 and 35 abut against the forward ends of the grooves 31, 36 and 37 in the side members of the frame. The bars 30, 34 and 35 are also shifted bodily rearwardly with the keyboard frame and the slides 55, 56, 58 and 59, 30 said slides moving into close relation with each other and passing from the ways 75 into the ways 22 on the main frame part, thus compacting the keyboard from front 35 to rear by shifting the space bar and the several banks of keys into close relation with each other and simultaneously moving the compacted keyboard within the main frame part beneath the type bars. As the cross-bar 14 of the keyboard frame moves rearwardly the jointed space bar levers 18 collapse as shown in Fig. 3, the pivots 24 and 27 being offset at opposite sides of the levers and out of alinement with the pivots 23, 25, 40 45 and 28 when the levers are in their normal extended operative positions. The sets of key levers 38, 50 and 52 operated by the banks of keys 9, 10 and 11 are also collapsed when the keyboard frame is moved rearwardly, as shown in Figs. 3 and 6, the pivots 45 and 48 of the levers 38 and the corresponding pivots of the levers 50 and 52 being 50 out of alinement and at one side of the remaining pivots connecting the several sections of the respective levers together. A transverse bar 78, held at its ends to the side walls 2 of the main frame part, extends across the machine at the rear of the links 41 and closely adjacent the pivots 40 and 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
- of the main frame part, as shown in Figs. 3 and 6, the main frame part and plate 7 thus serving as a casing to completely enclose the key action. Any suitable locking means may be provided for holding the plate 70 75 in its folded position.
- The extent of the outward movement of the keyboard frame is limited by the engagement of slide 55 with the stops 79 at the outer ends of the ways 75 and also by the two pairs of lazy tongs mechanisms. The extent of inward and outward movement of the slide 21, carrying the four pivot rods 19, 43, 51 and 53, is limited by two stops 80 held to the bottom plate 1 of the main frame. The inward movement of slide 21 is limited by the engagement of said slide with the bases of the stops 80, as shown in Figs. 3 and 6, and the outward movement of the slide is limited by the engagement of the standards 20 with the outwardly bent ends of the forwardly extending arms of said stops, as shown in Figs. 1 and 2. The stops 80 and the rear pair of lazy tongs determine the position of the slide 59 and plate 35 carrying the innermost bank of keys 11, the posts 69 being provided with pins 81 (Fig. 5) adapted to engage sleeves 74 and limit the degree of expansion of the rear pair of lazy tongs connecting posts 61, 70 and 69. The forward pair of lazy tongs connecting the posts 54, 57, 60 and 61 determine the relative positions of slides 55, 56, 58 and 59, and bars 14, 30, 34 and 35, the degree of expansion of said lazy tongs being limited by stops 79 and also by pins 82 on posts 54, 50 said pins being adapted to engage the sleeves 67 to limit the expansion of the lazy tongs. It will thus be seen that means is provided for insuring the proper positioning of the space bar and the several banks of keys when the key action is extended. The sets of lazy tongs also serve to prevent the sets of collapsible levers 18, 38, 50 and 52 from being extended sufficiently to bring the pivots 24 and 27 of levers 18, the pivots 45 and 48 of levers 38, and the corresponding pivots of levers 50 and 52 into alinement with the remaining pivots connecting the several sections of said levers together.
- What I claim is:—
1. In a collapsible typewriting machine, the combination of a main frame part, type bars mounted on the main frame part, a keyboard movable rectilinearly fore and aft of the machine relatively to the type bars from a normal extended operative position to a more compact inoperative position, and collapsible levers pivotally supported on the main frame part and having positive constantly maintained connections with the keys of the keyboard and the type bars.
  2. In a collapsible typewriting machine, the combination of a main frame part, type bars mounted on the main frame part, a

keyboard movable rectilinearly fore and aft of the machine relatively to the type bars from a normal extended operative position to a more compact inoperative position, and 5 collapsible levers pivotally supported intermediate their ends, said levers being positively connected at their forward ends with the keys of the keyboard and being positively connected at their rear ends with the 10 type bars.

3. In a typewriting machine, the combination with the type-bars of a compactible key action embodying pivoted vertically vibratable key-operated levers having constantly 15 maintained mechanical connections with the type bars and each formed of relatively foldable hinged sections positively connected together to fold horizontally.

4. In a typewriting machine, the combination with the type bars of a rectilinearly compactible key action embodying pivoted key-operated levers having constantly maintained mechanical connections with the type bars and each formed of relatively foldable 25 sections positively and pivotally connected together.

5. In a typewriting machine, the combination with the type bars of a compactible key action embodying pivoted key-operated levers having constantly maintained mechanical connections with the type bars and each formed of relatively foldable sections 30 positively and pivotally connected together, the axes of the pivots connecting the several sections of each lever together extending at right angles with the axis of the pivotal point of the lever.

6. In a typewriting machine, the combination of a frame, upwardly and rearwardly 40 movable type bars pivotally supported on the frame, horizontally collapsible key-operated levers pivotally supported on the frame intermediate their ends, and links pivotally held at their lower ends to the rear 45 ends of said key-operated levers and pivotally connected at their upper ends with the type bars.

7. In a typewriting machine, the combination of a frame, upwardly and rearwardly 50 movable type bars pivotally supported on the frame, horizontally collapsible key-operated levers pivotally supported on the frame intermediate their ends, and links pivotally held at their lower ends to the rear 55 ends of said key-operated levers and pivotally connected at their upper ends with the type bars forwardly of the type bar pivots.

8. In a typewriting machine, the combination of a frame, upwardly and rearwardly 60 movable type bars pivotally supported on the frame, key-operated levers pivotally supported in the frame intermediate their ends and having relatively foldable portions forwardly of their fulcrums pivotally connected together, and links pivotally con- 65

nected at their lower ends with the rear ends of said levers and pivotally connected at their upper ends with the type bars forwardly of the type bar pivots.

9. In a typewriting machine, the combination of a main frame, upwardly and rearwardly movable type bars pivotally supported in the main frame, a keyboard having a plurality of banks of keys, collapsible key operated levers pivotally supported in the main frame and positively connected with the keys and type bars at all times, and means whereby the banks of keys may be moved into compact relation with each other and simultaneously shifted bodily beneath the type bars to reduce the length of the machine from front to rear. 70 75 80

10. In a typewriting machine, the combination of a main frame, upwardly and rearwardly movable type bars pivotally supported in the main frame, a keyboard having a plurality of banks of keys, collapsible key operated levers pivotally supported in the main frame and positively connected with the keys and type bars at all times, means 85 whereby the banks of keys may be moved into compact relation with each other and simultaneously shifted bodily beneath the type bars to reduce the length of the machine from front to rear, and means for 90 properly positioning the banks of keys when the keyboard is extended. 95

11. A typewriting machine having a compactible key action, and means whereby a uniform relative movement may be imparted 100 to the parts of the key action when the key action is extended and compacted.

12. A typewriting machine having a compactible key action, and lazy tongs mechanism for imparting a uniform relative 105 movement to parts of the key action when the key action is compacted and extended.

13. A typewriting machine having a compactible keyboard comprising a space-bar and a plurality of rows of keys arranged 110 in banks, means whereby the banks of keys and the space bar may be simultaneously moved horizontally relatively to each other from their normal operative positions into more compact relation, and means whereby 115 the compacted keyboard may be shifted bodily into more compact relation with another part of the machine.

14. A typewriting machine having a compactible keyboard comprising a space bar 120 and a plurality of rows of keys supported in banks, and means whereby the space bar and the several banks of keys may be simultaneously moved horizontally relatively to each other from their normal extended operative positions into more compact relation with each other and into more compact relation with another part of the machine. 125

15. A typewriting machine having a compactible keyboard comprising a space bar 130

- and a plurality of rows of keys supported in banks, means whereby the space bar and the several banks of keys may be simultaneously moved horizontally relatively to each other from their normal extended operative positions into more compact relation with each other and into more compact relation with another part of the machine, and means for limiting the extent of the relative movement 5 between the space bar and the banks of keys.
16. A typewriting machine having a compatible keyboard comprising a space bar and a plurality of rows of keys supported in banks, means whereby the space bar and the several banks of keys may be simultaneously moved horizontally relatively to each other from their normal extended operative positions into more compact relation with each other and into more compact relation 15 with another part of the machine, means for limiting the extent of the relative movement between the space bar and the banks of keys, and means for limiting the extent of the bodily movement of the keyboard.
17. In a typewriting machine, the combination of a main frame part, type bars mounted on the main frame part, a compatible and bodily shiftable keyboard comprising a plurality of rows of keys supported in banks, constantly maintained positive mechanical operating connections between the keys of the keyboard and the type bars, and means for simultaneously shifting the several banks of keys from their normal 30 extended operative positions into closer relation with each other and into more compact relation with the type bars.
18. In a typewriting machine, the combination of a main frame part, type bars mounted on the main frame part, a compatible and bodily shiftable keyboard comprising a plurality of rows of keys supported in banks, constantly maintained positive mechanical operating connections 40 between the keys of the keyboard and the type bars, and lazy tongs mechanism for shifting the several banks of keys relatively to each other from their normal extended operative positions into closer relation with each other and simultaneously moving the banks of keys into more compact relation with the type bars.
19. In a typewriting machine, the combination of a main frame, upwardly and rearwardly movable type bars pivotally supported in the main frame, a compactible keyboard having a plurality of banks of keys, constantly maintained positive mechanical operating connections between the 55 keys and type bars, and lazy tongs mechanism for shifting the banks of keys into compact relation with each other and simultaneously moving the keyboard to a compact inoperative position within the main frame under the type bars.
20. In a typewriting machine, the combination of a main frame, upwardly and rearwardly movable type bars pivotally supported in the main frame, a compactible keyboard having a plurality of banks of 70 keys, constantly maintained positive mechanical operating connections between the keys and type bars, lazy tongs mechanism for shifting the banks of keys into compact relation with each other and simultaneously moving the keyboard to a compact inoperative position within the main frame under the type bars, and means for limiting the extent of expansion and contraction of said lazy tongs mechanism. 75
21. In a collapsible typewriting machine, the combination of a main frame part, type bars supported on the main frame part, a keyboard frame part slidably held to move into and out of the main frame part, a plurality of banks of keys operatively connected to actuate the type bars, and means controlled by the movement of the keyboard frame part for imparting a uniform relative movement 80 between the banks of keys.
22. In a collapsible typewriting machine, the combination of a main frame part, type bars supported on the main frame part, a keyboard frame part slidably held to move into and out of the main frame part, a plurality of banks of keys operatively connected to actuate the type bars, and lazy tongs mechanism operable by the movement of the keyboard frame part for imparting a uniform relative movement to the banks of 90 keys. 95
23. In a collapsible typewriting machine, the combination of a main frame part, type bars supported on the main frame part, a keyboard frame part slidably held to move into and out of the main frame part, a plurality of banks of keys operatively connected to actuate the type bars, lazy tongs mechanism operable by the movement of the keyboard frame part for imparting a uniform relative movement to the banks of 100 keys, and means for limiting the extent of the expansion and contraction of the lazy tongs mechanism. 110
24. In a collapsible typewriting machine, the combination of a main frame part, type bars supported on the main frame part, a keyboard frame part slidably held to move into and out of the main frame part, a plurality of banks of keys operatively connected to actuate the type bars, means controlled by the movement of the keyboard frame part for imparting a uniform relative movement between the banks of keys, and means for limiting the extent of the sliding movement of the keyboard frame part. 115 120
25. In a collapsible typewriting machine, the combination of a main frame part, a keyboard frame part slidably held to the main frame part and movable from a nor- 125 130

mal extended position to a compact position within the main frame part, type bars mounted on the main frame part, a plurality of banks of keys operatively connected with the type bars, and means actuated upon movement of the keyboard frame part for moving the banks of keys relatively to each other and the keyboard frame part and shifting all of the banks of keys bodily 10 relatively to the type bars.

26. In a collapsible typewriting machine, the combination of a main frame part, a keyboard frame part slidably held to the main frame part and movable from a normal extended position to a compact position within the main frame part, type bars mounted on the main frame part, a plurality of banks of keys, key-operated levers positively connected with the keys and type 15 bars and having relatively foldable pivotally connected sections, and means controlled by the movement of the keyboard frame part into the main frame part for collapsing said key-operated levers and 20 simultaneously shifting the banks of keys into closer relation with each other and moving said banks of keys within the main frame part.

27. In a collapsible typewriting machine, the combination of a main frame part, a keyboard frame part slidably held to the main frame part and movable from a normal extended position to a compact position within the main frame part, type bars 35 mounted on the main frame part, a plurality of banks of keys, key-operated levers positively connected with the keys and type bars and having relatively foldable pivotally connected sections, and lazy tongs 40 mechanism controlled by the movement of the keyboard frame part for imparting a uniform relative movement between the banks of keys and shifting said banks of keys bodily into and out of the main frame 45 part.

28. In a collapsible typewriting machine, the combination of a main frame part, type bars mounted on the main frame part, a keyboard having a plurality of banks of 50 keys, a plurality of groups of levers pivotally supported intermediate their ends, or a plurality of superposed rods extending transversely of the main frame part, each group of levers being supported on a different rod and positively connected with one bank of keys at their forward ends and with their associated type bars at their rear ends, and means for shifting the banks of keys relatively to each other and for shifting 55 the banks of keys and the superposed pivot rods supporting the levers bodily relatively to the type bars.

29. In a collapsible typewriting machine, the combination of a main frame part, type 60 bars mounted on the main frame part, a

keyboard having a plurality of banks of keys, a plurality of groups of levers pivotally supported intermediate their ends on a plurality of superposed rods extending transversely of the main frame part, each 70 group of levers being supported on a different rod and positively connected with one bank of keys at their forward ends and with their associated type bars at their rear ends, and means for shifting the banks of 75 keys relatively to each other and for shifting the banks of keys and the superposed pivot rods supporting the levers bodily relatively to the type bars, each of said levers having relatively foldable pivotally connected sections at each side of its fulcrum.

30. In a typewriting machine, the combination of type bars, a keyboard having a plurality of banks of keys, a plurality of groups of foldable key-operated levers having shiftable fulcrums and positively connected with the keys and type bars, there being one group of levers for each bank of keys, and means for shifting the banks of 80 keys and the fulcrums of the key operated levers relatively to each other and to the type bars.

31. In a typewriting machine, the combination of type bars, a keyboard having a 95 plurality of banks of keys, a plurality of groups of foldable key-operated levers having shiftable fulcrums and positively connected with the keys and type bars, there being one group of levers for each bank of 100 keys, and lazy tongs mechanism for imparting a uniform relative movement to the banks of keys to extend and compact the keyboard and for shifting the keyboard and the fulcrums of the key operated levers 105 bodily relatively to the type bars to fold the key operated levers and move the keyboard into closer relation with the type bars.

32. In a typewriting machine, the combination of a main frame part, upwardly and rearwardly movable type bars pivotally supported on the main frame part, a keyboard frame part slidably held to move into and out of the main frame part below the type bars, a plurality of transversely extending slides supported at their ends in superposed ways formed on the keyboard frame part, a plurality of rows of vertically reciprocable key-supporting rods, the rods of each row being guided in apertures in one 115 of said slides, key operated levers having relatively foldable parts and positively connected with the key-supporting rods and type bars, and means controlled by the movement of the keyboard frame part for folding 120 and unfolding said levers and for imparting a relative movement to the slides to move the rows of key-supporting rods into and out of compact inoperative relation with each other.

33. In a typewriting machine, the combination of a main frame part, upwardly and rearwardly movable type bars pivotally supported on the main frame part, a keyboard frame part slidably held to move into and out of the main frame part below the type bars, a plurality of transversely extending slides supported at their ends in superposed ways formed on the keyboard frame part, a plurality of rows of vertically reciprocable key-supporting rods, the rods of each row being guided in apertures in one of said slides, key operated levers having relatively foldable parts and positively connected with the key-supporting rods and type bars, and lazy tongs mechanism controlled by the movement of the keyboard frame part for folding and unfolding said levers and for imparting a relative movement to the slides to move the rows of key-supporting rods into and out of compact inoperative relation with each other.

34. In a typewriting machine, the combination of a main frame part, upwardly and rearwardly movable type bars pivotally supported on the main frame part, a keyboard frame part slidably held to move into and out of the main frame part, a plurality of transversely extending slides supported in superposed ways on the keyboard frame part, a plurality of rows of key-supporting stems, the stems of each row being guided in apertures in one of the slides and movable forwardly and rearwardly with the slide, a plurality of superposed transversely extending pivot rods, a group of foldable key operated levers pivotally supported on each of said rods and positively connected with one of said rows of key-stems, links forming positive operating connections between the key operated levers and type bars, and means controlled by the movement of the keyboard frame part for shifting said slides relatively to each other and for bodily shifting all of said slides and the pivot rods of the key operated levers relatively to the type bars.

35. In a typewriting machine, the combination of a main frame part, upwardly and rearwardly movable type bars pivotally supported on the main frame part, a keyboard frame part slidably held to move into and out of the main frame part, a plurality of transversely extending slides supported in superposed ways on the keyboard frame part, a plurality of rows of key-supporting stems, the stems of each row being guided in apertures in one of the slides and movable forwardly and rearwardly with the slide, a plurality of superposed transversely extending pivot rods, a group of foldable key operated levers pivotally supported on each of said rods and positively connected with one of said rows of key-stems, links forming positive operating

connections between the key operated levers and type bars, and lazy tongs mechanism operable by the slidable keyboard frame part for shifting the slides relatively to each other and to the pivot rods and for bodily shifting all of said slides and pivot rods relatively to the type bars.

36. In a typewriting machine, the combination of a main frame part, upwardly and rearwardly movable type bars pivotally supported on the main frame part, a keyboard frame part slidably held to move into and out of the main frame part, a plurality of transversely extending slides supported in superposed ways on the keyboard frame part, a plurality of rows of key-supporting stems, the stems of each row being guided in apertures in one of the slides and movable forwardly and rearwardly with the slide, a plurality of superposed transversely extending pivot rods, a group of foldable key operated levers pivotally supported on each of said rods and positively connected with one of said rows of key-stems, links forming positive operating connections between the key operated levers and type bars, lazy tongs mechanism controlled by the movement of the keyboard frame part for shifting the slides relatively to each other and to the pivot rods and for bodily shifting all of said slides and pivot rods relatively to the type bars, and means for limiting the extent of expansion and contraction of the lazy tongs mechanism.

37. In a collapsible typewriting machine, the combination of a support, type bars mounted on the support, and a compactible key action for actuating the type bars comprising a plurality of horizontally extending rods shiftably mounted on the support, a plurality of groups of horizontally foldable key operated levers each group of levers supporting a bank of keys and being pivotally supported intermediate their ends on one of said rods, and positive operating connections between the rear ends of said levers and the type bars.

38. In a collapsible typewriting machine, the combination of a support, type bars mounted on the support, and a compactible key action for actuating the type bars comprising a plurality of horizontally extending rods shiftably mounted on the support, a plurality of groups of horizontally foldable key operated levers each group of levers supporting a bank of keys and being pivotally supported intermediate their ends on one of said rods, positive operating connections between the rear ends of said levers and the type bars, and means for imparting a uniform relative movement between the banks of keys supported by said groups of levers.

39. In a collapsible typewriting machine, the combination of a support, type bars mounted on the support, and a compactible

key action for actuating the type bars comprising a plurality of horizontally extending rods shiftably mounted on the support, a plurality of groups of horizontally foldable key operated levers each group of levers supporting a bank of keys and being pivotally supported intermediate their ends on one of said rods, positive operating connections between the rear ends of said levers and the type bars, means for imparting a uniform relative movement between the banks of keys supported by said groups of levers, and means for limiting the shifting movement of said horizontal pivot rods.

40. In a collapsible typewriting machine, the combination of a main frame part, type bars mounted on the main frame part, a plurality of pivot rods extending transversely of the main frame part and shiftable forwardly and rearwardly relative thereto, a plurality of groups of key operated levers each group of levers supporting a bank of keys and being pivotally mounted intermediate their ends on one of said rods, each of said levers being provided with pivotally connected horizontally foldable sections at opposite sides of its pivotal point, and positive operating connections between the rear ends of said levers and the type bars.

41. In a collapsible typewriting machine, the combination of a main frame part, type bars mounted on the main frame part, a plurality of pivot rods extending transversely of the main frame part and shiftable forwardly and rearwardly relative thereto, a plurality of groups of key operated levers each group of levers supporting a bank of keys and being pivotally mounted intermediate their ends on one of said rods, each of said levers being provided with pivotally connected horizontally foldable sections at opposite sides of its pivotal point, positive operating connections between the rear ends of said levers and the type bars, and means for imparting a uniform relative movement between the banks of keys supported by said groups of levers.

42. In a collapsible typewriting machine, the combination of a main frame part, type bars mounted on the main frame part, a plurality of pivot rods extending transversely of the main frame part and shiftable forwardly and rearwardly relative thereto, a plurality of groups of key operated levers each group of levers supporting a bank of keys and being pivotally mounted intermediate their ends on one of said rods, each of said levers being provided with pivotally connected horizontally foldable sections at opposite sides of its pivotal point, positive operating connections between the rear ends of said levers and the type bars, means for imparting a uniform relative movement between the banks of keys supported by said groups of levers, and means

for limiting the shifting movement of said horizontal pivot rods.

43. In a collapsible typewriting machine, the combination of a main frame part, type bars mounted on the main frame part, a keyboard movable horizontally relatively to the main frame part from a normal extended operative position to a more compact inoperative position in closer relation with the type bars, and horizontally collapsible levers pivotally supported on the main frame part and having positive constantly maintained connections with the keys of the keyboard and the type bars.

44. In a typewriting machine, the combination with the type bars of a compactible key action embodying vertically rockable key-operated levers fulcrumed intermediate their ends and having constantly maintained mechanical connections with the type bars, said levers each having hinged laterally shiftable sections at both sides of its fulcrum.

45. In a typewriting machine, the combination with the type bars of a compactible key action embodying pivotally supported key-operated levers having constantly maintained mechanical connections with the type bars and each formed of a plurality of sections foldable horizontally relatively to each other and positively and pivotally connected together.

46. In a typewriting machine, the combination of a frame, upwardly and rearwardly movable type bars pivotally supported in the frame, and a compactible key action for actuating the type bars comprising horizontally collapsible key-operated levers pivotally supported on the frame intermediate their ends, and links pivotally held at their lower ends to the rear ends of said key-operated levers and pivotally connected at their upper ends with the type bars forwardly of the type bar pivots.

47. In a typewriting machine, the combination of a main frame, upwardly and rearwardly movable type bars pivotally supported in the main frame, a keyboard having a plurality of banks of keys, horizontally collapsible levers pivotally supported in the main frame and positively connected with the keys and type bars at all times, and means whereby the banks of keys may be moved into compact relation with each other and simultaneously shifted bodily beneath the type bars to reduce the length of the machine from front to rear.

48. A typewriting machine having a horizontally compactible key action, and means whereby a uniform relative movement may be imparted to the parts of the key action when the key action is extended and compacted.

49. A typewriting machine having a horizontally compactible key action, and lazy

tongs mechanism for imparting a uniform relative movement to the parts of the key action when the key action is compacted and extended.

- 5 50. A typewriting machine having a compactible keyboard comprising a space bar and a plurality of rows of keys supported in banks, means for shifting the space bar and the several banks of keys horizontally relatively to each other from their normal extended operative positions into more compact relation with each other, and horizontally collapsible pivotally supported levers forming constantly maintained connections 70
10 between the keys and the space bar and the devices operated thereby.

- 15 51. In a collapsible typewriting machine, the combination of a main frame part, type bars supported on the main frame part, a keyboard frame part slidably held to move into and out of the main frame part, a plurality of banks of keys shiftable relatively to the keyboard frame part and movable therewith into and out of the main frame 85
20 part, horizontally foldable levers positively connected with the keys and the type bars, and means controlled by the movement of the keyboard frame part for imparting a uniform relative movement between the 90
25 banks of keys.

- 30 52. In a collapsible typewriting machine, the combination of a main frame part, type bars supported on the main frame part, a keyboard frame part slidably held to move into and out of the main frame part, a plurality of banks of keys shiftable relatively to the keyboard frame part and movable therewith into and out of the main frame part, horizontally foldable levers positively connected with the keys and the type bars, and a lazy tongs mechanism operable by the movement of the keyboard frame part for imparting a uniform relative movement to the banks of keys. 100
35
40

- 45 53. In a collapsible typewriting machine, the combination of a main frame part, a keyboard frame part slidably held to the main frame part and movable from a normal extended operative position to a compact position within the main frame part, type bars mounted on the main frame part, a plurality of banks of keys, horizontally foldable levers positively connected with the keys and type bars for actuating the 105
50
55 type bars when the keys are depressed, and means actuated by the movement of the keyboard frame part into and out of the main frame part for shifting the banks of keys relatively to each other and the keyboard frame part and shifting the banks of keys bodily relatively to the type bars.

- 60 54. In a collapsible typewriting machine, the combination of a main frame part, a keyboard frame part slidably held to the 115
65 main frame part and movable from a nor-

mal extended position to a compact position within the main frame part, type bars mounted on the main frame part, a plurality of banks of keys, levers positively connected with the keys and type bars and having pivotally connected sections foldable horizontally relatively to each other, and means controlled by the movement of the keyboard frame part into the main frame part for holding said key-operated levers and simultaneously shifting the banks of keys into closer relation with each other and moving said banks of keys within the main frame part. 75

55. In a collapsible typewriting machine, 80 the combination of a main frame part, a keyboard frame part slidably held to the main frame part and movable from a normal extended position to a compact position within the main frame part, type bars mounted on the main frame part, a plurality of banks of keys, levers positively connected with the keys and type bars and having pivotally connected sections foldable horizontally relatively to each other, and lazy tongs 90 mechanism controlled by the movement of the keyboard frame part for imparting a uniform relative movement between the banks of keys and shifting said banks of keys bodily into and out of the main frame 95 part.

56. In a typewriting machine, the combination of a main frame part, upwardly and rearwardly movable type bars pivotally supported on the main frame part, a keyboard frame part slidably held to move into and out of the main frame part below the type bars, a plurality of transversely extending slides supported at their ends in superposed ways formed on the keyboard frame part, a plurality of rows of vertically reciprocable key-supporting rods the rods of each row being guided in apertures in one of said slides, key operated levers positively connected with the key-supporting rods and the type bars having pivotally connected parts foldable horizontally relatively to each other, and means controlled by the movement of the keyboard frame part for folding and unfolding said levers and for imparting a relative movement to the slides to move the rows of key-supporting rods into and out of compact inoperative relation with each other. 100
105
110
115

57. In a typewriting machine, the combination of a main frame part, upwardly and rearwardly movable type bars pivotally supported on the main frame part, a keyboard frame part slidably held to move into and out of the main frame part below the type bars, a plurality of transversely extending slides supported at their ends in superposed ways formed on the keyboard frame part, a plurality of rows of vertically reciprocable key-supporting rods the rods of each row 120
125
130

being guided in apertures in one of said slides, key operated levers positively connected with the key-supporting rods and the type bars and having pivotally connected 5 parts foldable horizontally relatively to each other, and lazy tongs mechanism controlled by the movement of the keyboard frame part for folding and unfolding said levers and for imparting a relative movement to the 10 slides to move the rows of key-supporting rods into and out of compact inoperative relation with each other.

58. In a typewriting machine, the combination of a main frame part, upwardly and 15 rearwardly movable type bars pivotally supported on the main frame part, a keyboard frame part slidably held to move into and out of the main frame part, a plurality of transversely extending slides supported in 20 superposed ways on the keyboard frame part, a plurality of rows of key-supporting stems the stems of each row being guided in apertures in one of the slides and movable forwardly and rearwardly with the slide, a plurality 25 of superposed transversely extending pivot rods, a group of key operated levers pivotally supported on each of said rods and positively connected with one of said rows of stems and provided with pivotally connected 30 sections foldable horizontally relatively to each other, links forming positive operating connections between the key operated levers and type bars, and means controlled by the movement of the keyboard 35 frame part for shifting said slides relatively to each other and for bodily shifting all of said slides and the pivot rods of the key operated levers relatively to the type bars.

59. In a typewriting machine, the combination of a main frame part, upwardly and 40 rearwardly movable type bars pivotally supported on the main frame part, a keyboard frame part slidably held to move into and out of the main frame part, a plurality 45 of transversely extending slides supported in superposed ways on the keyboard frame part, a plurality of rows of key-supporting stems the stems of each row being guided in apertures in one of the slides and movable 50 forwardly and rearwardly with the slide, a plurality 55 of superposed transversely extending pivot rods, a group of key operated levers pivotally supported on each of said rods and positively connected with one of said 60 rows of stems and provided with pivotally connected sections foldable horizontally relatively to each other, links forming positive operating connections between the key operated levers and type bars, and lazy tongs 65 mechanism operable by the slidable keyboard frame part for shifting the slides relatively to each other and to the pivot rods and for bodily shifting all of said slides and the pivot rods relatively to the type bars.

60. In a typewriting machine, the combi-

nation of a main frame part, upwardly and rearwardly movable type bars pivotally supported on the main frame part, a keyboard frame part slidably held to move into and out of the main frame part, a plurality of 70 transversely extending slides supported in superposed ways on the keyboard frame part, a plurality of rows of key-supporting stems the stems of each row being guided in apertures in one of the slides and movable forwardly and rearwardly with the slide, a plurality of superposed transversely extending pivot rods, a group of key operated levers pivotally supported on each of said rods and positively connected with 80 one of said rows of stems and provided with pivotally connected sections foldable horizontally relatively to each other, links forming positive operating connections between the key operated levers and type bars, lazy 85 tongs mechanism operable by the slidable keyboard frame part for shifting the slides relatively to each other and to the pivot rods and for bodily shifting all of said slides and the pivot rods relatively to the type 90 bars, and means for limiting the extent of expansion of the lazy tongs mechanism.

61. In a collapsible typewriting machine, the combination of a main frame part having an opening at its forward side through 95 which the keyboard is shiftable, type bars mounted on the main frame part, longitudinally collapsible key-operated levers pivotally supported within the main frame and normally extending forwardly beneath the 100 type bars to points beyond the forward side of the main frame, a keyboard frame part slidably held to move into and out of the main frame part below the type bars, a plurality of rows of key-supporting stems connected with the forward ends of the key-operated levers, a plurality of transversely extending slides supported at their ends in the keyboard frame part and each provided with a row of apertures for guiding one row of 110 key stems, lazy tongs mechanism connected with said slides, and a frame plate hinged to the main frame part to swing upwardly and rearwardly from a horizontal position to a position closing the opening in the main 115 frame part.

62. In a collapsible typewriting machine, the combination of a main frame part having an opening at its forward side through which the keyboard is shiftable, type bars mounted on the main frame part, longitudinally collapsible key-operated levers pivotally supported within the main frame and normally extending forwardly beneath the type bars to points beyond the forward side 120 of the main frame, a keyboard frame part slidably held to move into and out of the main frame part below the type bars, a plurality of rows of key-supporting stems connected with the forward ends of the key 125 stems, lazy tongs mechanism connected with said slides, and a frame plate hinged to the main frame part to swing upwardly and rearwardly from a horizontal position to a position closing the opening in the main 130 frame part.

operated levers, a plurality of transversely extending slides supported at their ends in the keyboard frame part and each provided with a row of apertures for guiding one 5 row of key stems, lazy tongs mechanism connected with said slides, and a frame plate hinged to the main frame part to swing upwardly and rearwardly from a horizontal position to a position closing the opening in 10 the main frame part, and means on said frame plate for guiding the lazy tongs mechanism during movement thereof into and out of the main frame part.

63. A collapsible typewriting machine 15 comprising a main frame part, type bars

mounted thereon, a plurality of longitudinally collapsible key-operated levers operatively connected to actuate the type bars, keys connected with the forward ends of said levers, lazy tongs mechanism for collapsing and extending said levers to shift the keys into and out of the main frame part, and means foldable upwardly in front of the main frame part when the machine is collapsed for supporting the forward portion 20 of the lazy tongs mechanism when the machine is in its extended operative condition.

This specification signed this twelfth day of January, A. D. 1918.

PHILIPPE DE CLAMECY.
